UNITED STATES PATENT OFFICE.

WALTER R. JENNISON, OF ATLANTA, GEORGIA.

REFRIGERATOR.

1,007,702.

Specification of Letters Patent.

Patented Nov. 7, 1911.

Application filed June 23, 1910. Serial No. 568,562.

To all whom it may concern:

Be it known that I, WALTER R. JENNISON, a citizen of the United States, residing at Atlanta, in the county of Fulton and State of Georgia, have invented certain new and useful Improvements in Refrigerators; and I do hereby declare the following to be a full, clear, and exact description of the invention, such as will enable others skilled in the art to which it appertains to make and use the same.

This invention relates to improvements in refrigerators, and has for an object improved means for maintaining the water from the melting ice in the refrigerator until substantially all cooling effect thereof has been removed.

Another object of the invention is the arrangement in a refrigerator of means for creating a circulation of air within the refrigerator but not in contact with the interior of the produce chamber.

A still further object of the invention is the arrangement of a double walled refrigerator in which the walls are spaced apart, having apertures at the upper end thereof, whereby a free circulation of air may be had between the walls, and a plurality of pipes arranged between said walls for holding the water from the melting ice until the same has been deprived of substantially all of its cooling effect.

A further object of the invention is the arrangement of a refrigerator divided along the lower edge of the ice box or chamber, and arranged to be bodily moved so that the upper section or ice box may be turned so that the door therein may be at the front of the refrigerator or back as desired without interfering with the circulation of air and other cooling medium.

With these and other objects in view the invention comprises certain novel constructions, combinations, and arrangement of parts as will be hereinafter more fully described and claimed.

In the accompanying drawings: Figure 1 is a perspective view of one embodiment of the invention, certain parts being in section approximately on line 1—1 of Fig. 3. Fig. 2 is a section through Fig. 1 on line 2—2, the same being shown slightly separated for better illustrating the structure. Fig. 3 is a top plan view partly in section of the bot-

tom section shown in Fig. 2. Fig. 4 is a longitudinal vertical section through a refrigerator embodying a slightly modified form of the invention. Fig. 5 is a detail fragmentary perspective view showing the arrangement of the water carrying tube. Fig. 6 is a section through Fig. 4 approximately on line 6—6. Fig. 7 is a section through Fig. 6 on line 7—7.

In forming a refrigerator embodying the invention any desired material may be used, as for instance wood, glass, porcelain, clay, iron either cast or of the wrought variety, or a combination of these and other materials may be used as desired.

The refrigerator is divided into a produce chamber and what is known as an ice chamber, the ice chamber being entirely separated from the produce chamber so that there is no passage of air between the two chambers. Surrounding and forming the ice chamber and produce chamber are spaced walls which form therebetween an air-passage way for permitting a free circulation of air through the opening into the ice chamber entirely around the produce chamber. This circulation of air is around the produce chamber but does not enter therein. In order to assist this circulation of air in cooling the produce chamber the drainage from the ice chamber is held in a plurality of pipes or passage-ways between the walls of the refrigerator for a considerable time before the same is permitted to pass out entirely from the refrigerator, whereby the cooling effect of the low temperature drainage will be used for assisting in cooling the produce chamber.

Referring to Figs. 4 to 7 inclusive, 1 indicates the outer wall or housing, and 2 the inner wall or housing. The outer and inner walls when made of cast iron are joined at the corners, as shown in Fig. 3. The corners have arranged therein passage-ways 3 which receive the drainage through openings or apertures 4. The drainage passes down through passage-ways 3, through horizontal pipes 5 and 6, and again upward through vertical pipes 7 and 8. The pipes 7 and 8, and also pipe 9, are connected with a coupling member 10 slightly below the openings 4, so that the drainage will freely pass out through openings 4 but will be maintained at a height almost level with

the bottom of openings 4. When the drainage from ice chamber 11 has raised the water in pipes 7 and 8 up to member 10, any surplus water drained from chamber 11 through openings 4 will cause an equal amount of water to pass out the upper ends of pipes 7 and 8, and into pipe 9, from which it passes through a suitable drain pipe 12 to any desired place of disposal.

10 The inner wall 2 of ice chamber 11 is provided with a plurality of apertures 13 which permit the passage of air from the ice chamber into the sides of the refrigerator, and then back into the ice chamber. No opening is provided in the rear of the ice chamber so that the circulation of air is from the sides of the ice chamber to the sides, back and front of the produce chamber for maintaining the produce chamber in a 15 cooled condition. The doors 15 and 16 of the refrigerator may be made of any desired or usual construction.

In the drawings is disclosed a cast or molded refrigerator, but if a refrigerator 25 were made of wood or other material the passage-ways 3 would be provided by the extension of vertical pipes at the corners until the same open into the apertures or openings 4. In casting the refrigerator the 30 same, of course, may be cast either at one time or in parts as desired, as for instance, produce chamber 14 may be eliminated from the first casting and cast independently, after which it may be placed in position.

35 In Figs. 1, 2 and 3 an embodiment of the invention is shown, in which the refrigerator is made into two or more sections. In this form of the invention the ice chamber 17 is formed with side walls and a top. The 40 bottom 19' of said chamber may be made a part of either section or made a separate partition plate. The bottom edge of the side walls is formed with a notched out portion 18 which fits over the notched portion 45 19 in the lower part of the refrigerator. This will produce a tight joint and will readily permit the water to escape through openings 4 into the front passage-ways 3 from which it passes through pipes 20 and 50 21 to the bottom of the rear passage-ways 3. Pipes 22 and 23 are connected with the rear passage-ways 3 near the upper end thereof so that when the water rises in the rear passage-way 3 to a height slightly below openings 4 55 the same will pass into pipes 22 and 23 and from thence pass to fitting 24 and down discharge pipe 9, from which it may pass to any desired place. By this structure the refrigerator is cast in two or more parts and the 60 apertures in the corners thereof provided for the circulation of the cooling water from the ice chamber in such a manner that the cooling water is maintained for a maximum time in the refrigerator whereby the maximum cooling effect is produced. This effec-

tually assists and acts in combination with the circulation of air from the ice chamber into and through the space between the inner and outer walls. The vent at the top may be provided with a valve or pet-cock 70 for admitting or discharging air as desired, though ordinarily air may be refreshed sufficiently by the opening of the door to the ice chamber. Aside from these differences as set forth this form of refrigerator is the 75 same as that disclosed in Figs. 4 to 7 inclusive, and embodies the same principle of circulation of air and circulation of water for maintaining the produce chamber cool, and utilizing to the fullest extent the cooling 80 effect of the ice and meltage.

Other changes in the casing may be provided without departing from the spirit of the invention in the use of the drainage water from the ice chamber and the particular circulation of air around the produce chamber between the spaced walls of the refrigerator.

By the arrangement of the double walls as set forth the chilled air from the ice 90 chamber may circulate freely around the produce chamber but not within the same so that the ice chamber is not contaminated with any of the contents of the produce chamber, and yet the produce chamber is 95 cooled effectually. In addition to the circulation of the cooled or chilled air around the produce chamber, the additional cooling influence of the melted ice or drippings from the ice chamber is utilized.

100 The arrangement of the pipes or passage-ways around the produce chamber but not in communication therewith, presents means which causes the utilization of the cooling effect of both the circulation of chilled air 105 and the circulation of chilled water, in proximity to the produce chamber. From the structure set forth, therefore, it will be observed that a maximum amount of cooling effect is obtained by the use of drip or drainage, the circulation of chilled or cooled air and the holding of the cooled water resulting from the melting ice in proximity to the produce chamber until the chilling effect of the water has been substantially fully utilized.

110 What I claim is:

1. A refrigerator comprising a housing formed with spaced walls defining an ice chamber and a produce chamber, said walls 120 being divided intermediate their ends for producing a separate and independent receptacle as an ice chamber and as a produce chamber, said ice chamber being formed with apertures therein for permitting air 125 to pass therefrom into and from the space between said walls whereby air is adapted to circulate freely from said ice chamber around said produce chamber and means for causing all drainage water from said ice 130

chamber to circulate adjacent said produce chamber, in proximity to the air space surrounding the produce chamber.

2. A refrigerator comprising a housing formed with spaced walls divided transversely intermediate their length for defining an independent removable ice chamber and produce chamber, the walls of said ice chamber being formed with apertures for permitting air to circulate from said ice chamber between said walls, the walls of said produce chamber being provided with passageways therein opening into said ice chamber for receiving the drainage from said ice chamber and discharging slightly below the bottom of said ice chamber for retaining the drainage water from the refrigerator until substantially all of the cooling effect thereof has been utilized.

20 3. A refrigerator comprising a housing formed with an ice chamber, and produce chamber, a passage-way in the walls at each corner of said housing, pipes arranged in the bottom of said housing extending horizontally from said passageway, pipes in the walls of said housing extending vertically from said first mentioned pipes, and a discharge pipe positioned in one of the walls of said housing extending from the top of said vertical pipes, said ice chamber being formed with a plurality of apertures opening into said passage-ways at the corners of said housing, said apertures being above the top of said vertical pipes.

35 4. A refrigerator comprising a housing formed with spaced walls joined at the corners and provided with a passage-way in each corner, said housing being divided into an ice chamber and a produce chamber, said ice chamber being constructed with a plurality of air circulation apertures, and a drainage aperture for each of the passage-ways in said corners, whereby water may freely pass into the passage-ways in said corners from said ice chamber, and air may freely pass from said ice chamber into the space between said walls and along the outer surface of the interior wall, and a plurality of pipes having one end thereof extending upward to almost a line with the drainage apertures of said ice chamber.

5. A refrigerator comprising a housing formed with an independent upper ice chamber and an independent lower produce chamber, said housing being divided intermediate its length for permitting the removal of one of said chambers from the other, said housing being formed with a double wall spaced apart for forming an inclosed air space, the inner wall of said ice chamber being formed with apertures for permitting a free circulation of air through the space between said walls, means for directing water from the ice chamber downward through one face of the refrigerator,

a plurality of means for directing said water upward adjacent said produce chamber on the opposite side to the means for directing the water downward and means for finally discharging said water.

6. A refrigerator comprising a housing formed with spaced walls joined at the corners and provided with a passage-way at each corner, said housing comprising an independent ice chamber and an independent produce chamber, said ice chamber being formed with a pair of apertures extending to the front corner passage-ways, a pipe extending from the bottom of each of said front passage-ways to the bottom of each of the rear corner passage-ways, and a discharge pipe connected with said rear corner passage-ways near the upper ends thereof.

7. A refrigerator comprising a housing formed with spaced walls, joined at the corners, and provided with a passage-way in each corner, said housing comprising an ice chamber and a produce chamber, said ice chamber and produce chamber being independent receptacles and formed with interlocking portions for providing a joint when assembled, said ice chamber being constructed with a plurality of air apertures and means for guiding drainage water from said aperture to a point of discharge.

8. A refrigerator comprising a housing formed with an outer wall and an inner wall integrally connected at the corners, said corners being formed with passage-ways therein, a dividing plate arranged in said refrigerator for dividing the refrigerator into an ice chamber and a produce chamber, the inner walls of said ice chamber being formed with apertures for directing water from said ice chamber into said passage-ways in the corners of said walls, and also with apertures on two sides for permitting free circulation of air along the outer surface of said inner walls.

9. A refrigerator comprising a housing formed with an upper ice chamber and a lower produce chamber, said chambers being formed independent and separable, said housing being formed with double walls spaced apart and provided with means for free communication with said ice chamber, means for directing water from the ice chamber down through passageways formed in the front corners of said housing and a plurality of means for directing said water up through the back part of said housing and means for finally discharging said water at a point slightly below the bottom of said ice chamber whereby the drainage water is retained in the refrigerator until substantially all of the cooling effect thereof has been utilized.

10. A refrigerator comprising a housing formed with spaced walls, a partition arranged in said housing intermediate the

ends thereof for dividing said housing into an ice chamber and a produce chamber, said housing being divided into two parts intermediate the ends thereof at substantially the line of said partition for providing a refrigerator having a removable ice chamber, said ice chamber being formed with discharge apertures in a plurality of corners thereof, passage-ways leading from some of said apertures downward for receiving the drainage water from said ice chamber, pipes for directing the water from said passageways to the opposite side of the refrigerator and thence upward to a point slightly below the bottom of said ice chamber and a discharge pipe leading from the end of said second mentioned pipe.

11. A refrigerator comprising a housing formed with hollow walls and a partition member intermediate the ends of the housing, said member dividing said housing into an ice chamber and a produce chamber, said ice chamber being formed with a door opening to the exterior of the housing, and with an aperture opening into the hollow space in the wall of said housing, and drainage discharge openings, said produce chamber being formed with a door opening only, whereby said ice chamber and said produce chamber are independent non-communicating receptacles, and means for leading the discharge water from said discharge openings in proximity to said produce chamber and from thence to a discharge outlet slightly below the bottom of said ice chamber.

12. A refrigerator comprising a housing formed in a plurality of parts of cast mate-

rial, for defining an ice chamber and a produce chamber, the walls of said ice chamber and produce chamber being formed hollow and arranged so that the hollow portions of said walls will register when the parts are assembled, said ice chamber being formed with apertures on two sides for permitting the circulation of air from said ice chamber down through the hollow space of said walls, around said produce chamber and up past said produce chamber and into said ice chamber, means for leading the drainage water from said ice chamber into proximity to said produce chamber, but independent of the air circulation from the said apertures, and means for retarding the flow of the drainage water until substantially all of the cooling effect thereof has been utilized.

13. A refrigerator comprising a housing formed in two parts, defining an ice chamber and a produce chamber, the walls of said housing being formed hollow and in free communication with said ice chamber whereby a free circulation of air is provided from said ice chamber downward adjacent said produce chamber and back to said ice chamber, and means for simultaneously utilizing the cooling effect of the drainage water from said ice chamber, for augmenting the cooling effect of said circulation of air.

In testimony whereof I affix my signature in presence of two witnesses.

WALTER R. JENNISON.
